PAJAMA BAG DOLL

Florence Journer, 276 1st Ave, New York, N.Y.

Filed Mar. 12, 1964, Ser. No. 78,977

Term of patent 3½ years

(Cl. D34—4)

FIG. 2 is a rear perspective view thereof;

FIG. 3 is a side elevational view thereof;

FIG. 4 is a bottom plan view with the legs in a sitting position;

FIG. 5 is a front elevational view of my pajama bag doll representing a female figure;

FIG. 6 is a rear perspective view thereof;

FIG. 7 is a side elevational view thereof; and

FIG. 8 is a bottom plan view with the legs in a sitting position.

I claim:

The ornamental design for a pajama bag doll, substantially as shown and described.
